UNITED STATES PATENT OFFICE

HENRY C. A. MEYER, OF BALTIMORE, MARYLAND, ASSIGNOR, BY MESNE ASSIGNMENTS, TO UNITED STATES HOFFMAN MACHINERY CORPORATION, OF NEW YORK, N. Y., A CORPORATION OF DELAWARE

GARMENT PRESSING MACHINE

Application filed December 3, 1925. Serial No. 72,978.

This invention pertains to improvements in presses and more particularly to presses adapted for garment and laundry work. The invention is in a sense, an improvement upon the structure shown and claimed in the patent to William A. Zeidler, Patent Number 1,872,100 granted Aug. 16, 1932.

The main object of the present invention is to produce a structure which, while effecting the operations set forth in said application will be simpler and more positive in its operation.

A further object of the invention is to produce a press wherein the major portions thereof, at least the frame-work, may be produced from sheet metal, such as steel pressed to form, which has the advantage of lightening the structure as a whole while at the same time insuring stability when the same is subjected to stress and strain.

A still further object of the invention resides in the provision of means whereby the movement of the head will be positively controlled to first bring it into direct alignment with the head, and in spaced relation thereto, and to thereafter cause the head to move downwardly in a right line onto the goods imposed upon the buck. By reason of the arrangement and operation of the parts, the head moves to a considerable extent to the rear of the buck allowing free access to the buck whereby the operator may, without difficulty, secure a proper lay of the goods. Again, by reason of the downward right line movement of the head, no drag between the pressing element and the goods takes place.

A still further object of the invention resides in the provision of means whereby the power exerted for closing the press, that is to say, moving the head forwardly over the buck and then downwardly onto the buck, is exerted directly upon the head carrying frame rather than through the track and the rocking frame to which the head is attached.

With these and other objects in view, reference will be had to the annexed drawings wherein,

Figure 1 is a vertical sectional view of the press with the head and the rocking frame which carries the same moved to the extreme

rear position as shown in full lines, while in dotted lines, the press head is illustrated as moved over directly above the buck and in spaced relation thereto.

Figure 2 is a vertical sectional view taken on the line II—II of Figure 1 illustrating more particularly the pivotal support for the rear portion of the tilting platform upon which rests the rocker frame that carries the head,

Figure 3 is a sectional side elevation showing the press in its closed position, that is to say, with the head lowered upon the buck or upon the goods imposed upon the buck,

Figure 4 is a horizontal sectional view taken on the line IV—IV of Figure 3, and

Figure 5 is a transverse vertical sectional view taken on the line V—V of Figures 3 and 4.

As above noted, portions of the machine are preferably formed from sheet metal and to that end the base or main frame of the machine comprises an angle bar or member 1 substantially U-shaped in outline, see Figure 4, to the upstanding flange or element of 75 which is secured body elements or plates 2 and 3, which plates are riveted at their lower ends of said flange. These plates at their upper ends are riveted to a metal frame or casting 4 while at the rear portion of the angle 1 80 there is secured a cross block or frame 5 which ties the base 1 together and prevents any spreading thereof.

Secured upon the frame block 4 is a casting 6 to which in turn is secured a buck or pressing member 7 of any approved type or contour.

Extending upwardly from the frame block 5 are lugs 8 in which a cross bar 9 finds its bearings. Secured to the bar 9 is a pivoted 90 platform produced from bar metal bent generally to a U-form, said member being designated by 10. The side elements of said platform stand in parallel relation and in effect form a track upon which the rocking or rolling head carrying frame finds its bearing, as will be hereinafter set forth. The forward end or cross connecting element of the platform 10 is provided with brackets 11 in which are adjustably secured draw rods 12, the up- 100

per headed ends of which are externally threaded and screw into the lower end of springs 13. Each of said spring at its upper ends engages a threaded block 14, said blocks in turn being pivotally mounted upon a through shaft 15 which finds its bearings in lugs 16 formed as an integral portion of the frame member 4. The blocks are held in position upon the outwardly extending ends of the rods 15 by cotter-pins 17, Figure 5, or by any suitable means which permits the ready withdrawal of the blocks in case it becomes necessary at any time to replace the springs. The tension springs may be adjusted through the draw rods 12 in a manner which will be apparent to those skilled in the art.

The head of the machine, designated by 18, is secured to the forward overhanging portion of a rocking frame, which latter finds its bearing upon the pivoted platform 10. Said rocking head supporting frame, is shown, in the instant case, as produced from a stamping of sheet metal and two side plates or webs. The forward head supporting portion of the rocking frame is produced by stamping or dying out a sheet of metal to the form best shown in Figures 1 and 4. It may be said to comprise a body plate or transversely extending web-like member 19 having laterally and rearwardly extending flanges 20 which body and flanges at their upper portions are curved forwardly and form the overhanging element or elements to which the head 18 is secured. Secured to and extending rearwardly from each of the side flanges 20 are plates designated, respectively, 21 and 22, see Figure 4, the plates being widest at the bottom or, in other words, tapering away to practically nothing at their upper ends which terminate short of the forwardly curved portion of the main frame member 19—20. The lower edges of the side plates 21 and 22 are, as will be seen upon reference to Figures 1 and 2, curved and to each of the plates upon its outer face, adjacent such curved portions, there is secured a bar or bearing plate 23, which bars rest upon the rocking platform or more specifically, the side elements thereof, which form tracks for said bars. The side plates, as will be seen upon reference to Figures 1, 2 and 3, extend downwardly against the inner side faces of the track elements and thus the frame is held against lateral displacement with reference to the tracks.

When the press is open the parts stand in the position shown in full lines in Figure 1, the head being elevated and moved clear of the buck and to the rear thereof.

In the operation of the press the head moves forwardly to the dotted line position in Figure 1, and then downwardly to the pressing position shown in Figure 3.

In order to prevent undue lateral motion of the head and its carrying frame, and to in-

sure the head moving downwardly in a right line to pressing position after it has been brought over the buck, I provide the main frame with certain guide slots which cooperate with guide rollers secured to, and carried by, the rocking head supporting frame. In each of the side plates 2 and 3 there is provided two slots, the upper one having a rear portion 24 which is inclined slightly from the horizontal toward the front of the machine, and then with a vertically disposed portion 25. The lower slot is provided with an inclined upper portion 26 and a lower vertically disposed portion 27, the upper portion being only slightly inclined to the rear.

Owing to the fact that the side frame members 2 and 3 are produced from sheet metal and consequently would afford but small bearing for the guide rollers which cooperate with the slots, it is deemed advisable to secure bearing plates or members to said plates 2 and 3 which members are designated by 28 and shown in the instant case as castings riveted or otherwise secured to the frame members. Any suitable form of guide may, however, be employed.

Secured to the forward member 19 of the rocking frame are brackets 29 and 30, see Figures 1 and 5, in which are secured stub axles which form the support for the flanged rollers 31 and 32 which enter respectively the upper slots formed in the opposite frame members 2 and 3. A second pair of brackets 33 and 34 are secured to the lower portion of the frame member 19 and a rod 35 extends therethrough as will be best seen upon reference to Figure 5. Mounted upon the outer ends of this rod are flanged guide rollers 36 and 37 which extend through the lowermost slots in the respective side frame elements 2 and 3 and bear upon the members 28 secured to the frame member adjacent the lower pair of slots.

Secured to the lower central portion of the forward frame member 19 is another bracket 38, the rod 35 passing therethrough. The lower end of the bracket is bifurcated in order to permit the entrance of the reduced lower end of a coupling element 39. The upper end of this member is internally threaded to receive the lower threaded end of a rod 40. The upper end of the rod, see Figure 3, is reduced in diameter and passes through an opening formed in a swivel block 41 and to the upper end of the rod is secured a hand wheel or knob 42 through the manipulation of which the rod 40 may be screwed into, or out of the lower coupling member 39. Said member 39 and the rod 40 form the lower link element of a toggle mechanism, the upper element of which is produced by two bars or levers 43 and 44 which bars at their upper ends are pivotally mounted upon the shaft or rod 15. Said levers 43 and 44 stand in parallelism and are provided with open-

ings to receive the studs 45 formed upon the swivel block 41. Said levers extend downwardly to a point relatively close to the base of the machine and a pedal 46 is secured thereto. A spring-pressed latch 47 is pivotally secured to the under face of the pedal and the nose 48 of said latch is adapted, when the press is closed, to pass into an opening, see Figure 3, formed in the base element 1 and to come into locking engagement with said base thereby holding the press in its closed position. The latch is also provided with an upstanding lug 49 which protrudes upwardly through an opening formed in the pedal 46 whereby the operator may depress the latch and cause its release or disengagement from the frame thus permitting the press to be opened. A handle 50 is positioned between the forward ends of the flange members 20 in order that the operator may, if he so desires, move the head manually rather than through the pedal and toggle mechanism. The usual table 51 and back-board 52 will also be provided.

25 It will be understood that the press will be provided with the usual heating means for the head and buck, steam ejecting or spraying means and vacuum producing means but as these are well known in the art, it is not deemed necessary to illustrate or describe them.

30 The upper cam slots extend, as will be noted from the foregoing description, in a general upward and rearward direction and the head carrying frame or supporting member has an upright portion and an over-hanging portion, which latter carries the head 18. Furthermore, the head carrying frame or member has in effect a follower or followers 35 in the rollers which work in the slots and the head supporting member has means for actuating it to shift said member along the slots or cam grooves through the mechanism as above described.

45 In operation with the parts shown in full line position, Figure 1, in which case it will be seen that the toggle is broken, the operator will first place the goods upon the buck 7 and secure the desired lay thereof. He can 50 then either draw the head forwardly into the dotted line position through the use of the handle 50 or, what is preferable and desirable, owing to the fact that both hands may be maintained upon the garment, he will cause the head to move forwardly by moving the pedal inwardly to such an extent that the parts will come to the dotted line position in Figure 1. During this movement the guide rollers pass downwardly along the portion 24 of the upper slots and the upper portion 26 of the lower slots, the head supporting frame rocking or rolling upon the track of the pivoted supporting frame or platform. Further inward movement of the pedal will bring the parts to the position shown in Fig-

ure 3, the guide rollers absolutely insuring a right line downward movement of the head toward the buck onto the garment imposed thereon. The toggle coming to approximately straightened position will cause high 70 pressure to be exerted between the head and the buck. Inasmuch as the lower link of the toggle is connected directly to the rocking frame, the pressure is exerted directly through said rocking frame to the head and 75 not through the rocking platform to the rocking frame as in the constructions shown in the press first mentioned. Moreover, there is no tendency as in the press above mentioned for the track to separate from the 80 rocker frame and hence there is an absence of noise which inheres under the older construction when the press is opened owing to a hammering between the track and the rocking frame.

85 Guiding of the rocking frame by the rollers prevents any undue lateral motion of the parts thereby insuring the complete register between the head and the buck at all times.

The fact that the head supporting and carrying frame is formed of sheet steel, it will yield to a certain extent and always come back to position. Thus if a thick portion of a garment be placed upon one end of the buck, or a portion of a garment be placed upon one end only, the frame will compensate for this variation in thickness; in other words, the frame may be carried out of its normal position up to the elastic limit of the metal without fear of breakage and with the assurance that it 95 will always return to proper alignment.

90 What is claimed is:

1. In a press of the class described, the combination of a frame; a buck mounted thereon; a platform pivoted to the frame; resilient means normally acting to raise the free end of the platform; a rocker frame mounted on the platform; a pressing head carried at the upper end thereof; and a pressure applying mechanism interposed between the forward lower portion of the rocker frame 105 and a fixed portion of the press.

2. In a press of the class described, the combination of a frame; a buck mounted thereon; a platform pivoted to the frame; resilient means normally acting to raise the free end of the platform; a rocker frame mounted on the platform, a pressing head at the upper end thereof; and pressure applying means involving a toggle mechanism 115 interposed between the lower forward portion 120 of the rocker frame and a fixed portion of the press.

3. In a press of the class described, the combination of a frame; a buck mounted thereon; a platform pivoted to the frame resilient means normally acting to raise the free end of the platform; a rocker frame mounted on the platform; a pressing head carried at the upper end thereof; and a pressure applying means involving a toggle mechanism in- 130

terposed between the lower forward portion of the rocker frame and a fixed portion of the press, one of the links of the toggle extending downwardly and carrying a pedal.

5 4. In a press of the class described, the combination of a frame; a buck mounted thereon; a platform pivoted at its rear at the rear portion of the frame; resilient means acting on said platform to move it upwardly; a rocker frame mounted on the platform; a head secured to the upper portion of said rocker frame; and means acting directly upon the forward lower portion of said rocker frame to rock the same forwardly and then to move the same downwardly.

15 5. In a press of the class described, the combination of a frame including two vertically disposed parallel side elements each having two guide slots formed therein; a tiltable platform; resilient means normally acting to raise the free end of the platform; a rocker frame mounted on the platform; guide rollers associated with the frame and extending into the guide slots; a buck; a head carried by the rocker frame; and means for forcing the buck and head into pressing relation.

30 6. In a press of the class described, the combination of a base; a pair of sheet metal side plates extending upwardly therefrom, each plate having formed therein a pair of guideways; a frame member securing the upper ends of said plates together; a buck mounted thereon; a platform pivotally mounted at the rear portion of the base; resilient means normally serving to raise the forward end thereof; a rocker frame mounted on the platform; a head carried thereby; flanged guide rollers carried by the rocker frame, said rollers entering the guideways aforesaid with the flanges bearing against the side plates; and means for moving the head forwardly and into pressing relation with reference to the buck.

45 7. In a press of the class described, the combination of a base; a pair of sheet metal side plates secured to and extending upwardly therefrom; each plate having formed therein two guideways and each way having an inclined upper portion and a vertically disposed lower portion, a frame member securing the upper ends of said plates together; a buck mounted thereon; a platform pivotally mounted at the rear portion of the base; resilient means normally serving to raise the forward end thereof; a rocker frame mounted on the platform; a head carried thereby; flanged guide rollers carried by the rocker frame, said rollers entering the guideways aforesaid with the flanges bearing against the side plates; and means for moving the head forwardly and into pressing relation with reference to the buck.

50 8. In a press of the class described, the combination of a frame; a buck mounted thereon;

a platform pivoted at the rear portion of the frame; resilient means acting on said platform to rock it upwardly; a rocker frame mounted on the platform; a head secured to the upper portion of said rocker frame; and means interposed between the rocker frame and the frame first mentioned for insuring first a forward movement of the head over the buck and in spaced relation thereto, and thereafter a right line movement of the head toward the buck said means acting directly upon the forward lower portion of said rocker frame to force the buck and head into pressing relation.

70 9. In a press of the class described, the combination of a main frame; a buck carried thereby; a platform pivotally mounted at the rear portion of the lower part of the frame; resilient means normally acting to raise the forward end of said platform; a rocker frame mounted upon the platform; a head carried at the upper portion of said rocker frame; and means interposed between a fixed portion of the press and the forward lower portion of the rocker frame for moving the head downwardly into pressing relation with the buck.

80 10. In a press of the class described, the combination of a base; a pair of sheet metal side plates extending upwardly therefrom; a casting connecting the upper ends of said plates; a platform pivotally mounted at its rear end to the rear portion of the base; resilient means normally acting to raise the forward end of said platform; a rocker frame, said frame comprising a body member formed of sheet metal having rearwardly extending flanges at each side thereof, with the upper portion carried forwardly to provide an overhanging member, and a pair of plates secured to the flanges and extending rearwardly therefrom, the lower ends of the said plates being curved in outline; a head carried by the forwardly extending portion of said rocker frame; tracks secured to said last named plate members, said tracks resting upon the pivoted platform; and means for swinging the rocker frame forwardly and moving the same downwardly to bring the head into pressing relation with the buck.

95 11. In a press of the class set forth in claim 10; guide rollers carried by the rocker frame and guideways formed in the side plates, said rollers working in said guideways.

120 12. In a press of the class described, the combination of a frame; a buck mounted thereon; a platform pivoted to the frame; resilient means acting normally to raise the forward end of the platform; a rocker frame mounted on the platform; a pressing head carried at the upper end thereof; a pressure applying means involving a toggle mechanism interposed between the lower forward portion of the rocker frame and a fixed portion of the press; a pedal secured to the lower extended portion of one of the links of the toggle; and a latch carried by the pedal

adapted to engage a fixed portion of the press when the toggle is moved to its operative pressing position.

13. In a garment pressing machine, the combination of a supporting frame; a buck mounted thereon; a head; a supporting member for said head, said member having a downwardly extending portion and an upper forwardly extending portion to which latter the head is attached, said supporting member comprising a structure formed from sheet metal bent to form and being of U-shape substantially throughout its length whereby flanges are produced as extensions from the main body portion of said supporting member; and means for actuating said head-carrying supporting member to carry the head into and out of pressing relation with the buck.
- 20 14. In a garment pressing machine the combination of a supporting frame; a buck mounted thereon; a head supporting member formed from sheet metal bent to form, said member being substantially U-shape in cross section and having a downwardly extending portion and an overhanging forwardly extending portion, said supporting member presenting a substantially continuous and unbroken surface throughout its length; a head attached to said forwardly extending portion; and means for shifting said head supporting member to move the latter into and out of pressing relation with the buck.

In testimony whereof I have signed my name to this specification.

HENRY C. A. MEYER.
